UNITED STATES PATENT OFFICE.

IRVING WILLIAM ROSS, OF CHICAGO, ILLINOIS.

STRIPPING MACHINE.

Application filed December 7, 1925. Serial No. 73,607.

My invention relates to a stripping machine, more particularly to a machine for stripping off the fatty material adhering to beef skins which are to be employed as casings for receiving sausage meat, and the main object of my invention is the provision of an improved machine of this class which will embody certain desired features of simplicity, efficiency and convenience. Another object of my invention is the provision of a machine of this class in which a pair of milled cylinders are arranged to serve as means for stripping off the fatty material and in which one of the milled cylinders is mounted for treadle operated adjustment during the stripping operations.

Other objects will appear hereinafter.

The invention consists in the combinations and arrangements of parts hereinafter described and claimed.

The invention will be best understood by reference to the accompanying drawings forming a part of this specification, and in which,

Fig. 1 is a front elevational view of a machine embodying my improvements;

Fig. 2 is a top plan view of my machine;

Fig. 3 is a sectional detail showing the pivot bearing head for one end of the adjustable shaft, this view being taken on the line 3—3 of Fig. 2;

Fig. 4 is a longitudinal sectional view taken on the line 4—4 of Fig. 2;

Fig. 5 is a vertical sectional view taken on the line 5—5 of Fig. 2; and

Fig. 6 represents a longitudinal section through the cylinder on the adjustable shaft, this section being taken on the line 6—6 of Fig. 5.

In carrying out my invention I may employ any suitable frame structure for the support of the working parts; the frame structure shown including leg supported top strips 7 and 8 which are connected by suitable tie rods 9, the supporting legs 10 being connected below the top strips 7 and 8 with any suitable bracing members or strips.

The means for stripping off fatty material from the casings comprises a pair of stripping cylinders 11 and 12, each milled to provide sharp milling cutters 13. These cylinders are constructed alike, the structure thereof being illustrated in Fig. 6, which consists of a longitudinal section of cylinder 12 and from which it will be seen that the

milling cutters 13 are produced on a cylindrical body 14 mounted upon circular end pieces 15, the means of securement upon the end pieces comprising screws 16 which are countersunk in the cylindrical body and tapped into the circular end pieces 15.

Cylinders 11 and 12, thus preferably constructed, are secured upon the ends of the respective shafts 17 and 18 in front of the front strip 7 as best shown in Fig. 2. The shaft 17 is operatively mounted in a fixed position while the shaft 18 is operatively mounted for adjustment towards and away from the shaft 17. More specifically, the shaft 17 is operatively mounted upon the strip 7 by being rotatably arranged in a bearing block 19 which is bolted upon the strip 7, and in the bearing block cap 20 which is bolted upon the bearing block 19. The rear end of the shaft 17 is rotatably mounted in the bearing block 21 and bearing block cap 22, the said block 21 being bolted upon the strip 8, while cap 22 therefor is bolted upon the block 21. The rear end of the shaft 18 is mounted for pivoting movement towards and away from the shaft 17. To this end, I preferably employ a bearing head 23, made with pivot studs 24 and 25, said head 23 being arranged in a suitable opening 26 provided between the bearing block 21 and cap 22 therefor, with the pivot stud 24 having turning fit in the block 21 and with the pivot stud 25 having similar fit in the cap 22. The bearing head 23 is thus mounted for pivoting on a vertical axis comprising the pivot studs 24 and 25, and the rear end of the shaft 18 is rotatably journaled in this bearing head 23.

The forward end of the shaft 18 is journaled for sliding movement; and the means for carrying out this purpose consists in providing a slideway 27 in the bearing block 19 and in rotatably mounting the shaft 18 in a bearing head 28 arranged for sliding movement in said slideway. Screw elements 29, tapped through walls 30 defining the ends of the slideway, serve as stops for limiting the adjustment of the bearing head 28 in the slideway.

As best illustrated in Fig. 6 the bearing head 28 is provided with an extension 31; and astride of this extension is the forked end 32 of a shifting arm 33 which is pivoted at 34 to the frame brace 35, so that the pivoting of the shifting arm 33 upon the

pivot 34 will adjust the stripping cylinder 12 relatively to the opposing stripping cylinder 11. For pivoting the shifting arm 33 I preferably employ a treadle 36 pivoted 5 at one end on an axis 37 journaled at one end in a lug 38 and at the other end in a plate 39, said lug and said plate both upstanding from a floor plate 40. The treadle 36 is provided with a pin 41 which works in 10 a slot 42 provided for the purpose in the upstanding plate 39. A connecting rod 43 pivotally connects said pin 41 with the lower end of the shifting arm 33. The treadle 36 is normally held in elevated position by 15 a pull spring 44 which is connected at 45 to the treadle and at 46 to the floor plate 40. By this arrangement the adjustment of the stripping cylinder 11 is readily effected by the foot while said cylinders are being rotated. The cylinder 12 is normally drawn 20 away from the cylinder 11 by means of a pull spring 47 which is connected at 48 to the shifting arm 33 and at 49 to the bearing block cap. The treadle arrangement with 25 respect to this spring is such that the depression of the treadle will move the cylinder 12 towards the cylinder 11, while, under the release of the treadle, the spring 47 will draw the cylinder 12 away from the cylinder 11. 30 In Fig. 6, I illustrate the preferred mode of keying the cylinder 12 to its shaft. The key 50 on the shaft is bevelled at 50° towards the threaded end 51 of the shaft. The co-operating end piece 15 of the cylinder is 35 suitably grooved to receive the tapering key 50. The cylinder having been mounted on its shaft and engaged with the key 50 is then secured by means of the thumb screws 52 and a nut 53. The stripping cylinder 11 40 is secured in like manner upon its shaft.

Adjacent the strip 8 the shafts 17 and 18 are provided with the respective conjoined gears 54 and 55; and the shaft 17 is provided with a pulley 56 which is driven by a belt 45 57 from a driving pulley 58. In view of this gearing arrangement the stripping cylinders 11 and 12 are rotated towards each other and in a direction to cast the matter cut or stripped from the casing 59 towards the 50 ground, as the casing 59 is drawn upwardly in a position between the revolving cylinders and over an idler 60 by means of the drawing action of a reel 61 to which the casing is attached and which is revolved in the direction indicated by the arrow 62. The reel 61 is carried by a shaft 63 suitably mounted upon the strips 7 and 8. The shaft 63 carries a large driving wheel 64 which receives its power through a driving belt 65 from a 55 pulley 66, which in turn is driven from the driving pulley 58.

From the foregoing description taken in connection with the accompanying drawings, it will be understood that I provide a simple and effective treadle operated arrangement

whereby to remove the fatty material from the casing as it is drawn between the milling cutters and is wound upon the reel 61.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A machine of the kind set forth including a pair of stripping cylinders arranged to operate on a casing passing between them; means for moving one cylinder at an angle to the other during the stripping operation, and means for automatically returning said moving cylinder to position after being moved, said means being adjustably regulated by instrumentalities connected therewith substantially as described.

2. A machine of the kind set forth including a pair of stripping cylinders; a pair of rotatable shafts, said cylinders being fixed on said shafts to operate on a casing passing between them; fixed and movable bearings for said shafts; means for moving one of said movable bearings during the rotation of said shafts, and means for automatically returning said movable bearing to normal position after being moved, said means being adjustably regulated by instrumentalities connected therewith substantially as described.

3. A machine of the kind set forth including a frame; a pair of shafts having operative bearing therein and carrying co-operating stripping cylinders at corresponding ends thereof; the bearings for one of said shafts comprising a slidable bearing head adjacent the cylinder thereon and a pivoted bearing head at the end remote from said cylinder; means for shifting said slidable bearing head during the rotation of said shaft in the pivoted and slidable bearing heads, and means for automatically returning said slidable bearing head to normal position after being shifted, said means being adjustably regulated by instrumentalities connected therewith substantially as described.

4. A machine of the kind set forth including a pair of stripping cylinders; a pair of rotatable shafts, said cylinders being fixed on said shafts to operate on a casing passing between them; fixed and movable bearings for said shafts; means for shifting the shaft having the movable bearings during the rotation of said shafts to vary the distance between said cylinders; a reel having means for attaching the end of the cas-

ing thereto for drawing the casing between said cylinders, means for driving said shafts and said reel, and resilient means for automatically returning to position said shaft having the removable bearing, said resilient means being adjustably regulated by instrumentalities connected therewith substantially as described.

5. A machine of the kind set forth including a frame; a pair of shafts having operative bearing therein and carrying co-operating stripping cylinders at corresponding ends thereof; the bearings for one of said shafts comprising a slideable bearing head adjacent the cylinder thereon and a pivoted bearing head at the end remote from said cylinder; a pivoted arm engaging with said slideable bearing head; a pivoted treadle; an operative connection between said treadle 20 and said arm, and means to resiliently return said slideable bearing head to normal position after operation, said means being adjustably regulated by instrumentalities connected therewith substantially as described.

6. A machine of the kind set forth including a pair of stripping cylinders arranged to operate on a casing passing between them; means for drawing a sausage casing 30 between said cylinders; means for rotating said cylinders towards each other in a direction opposing the movement of the sausage casing; means for moving one cylinder at an angle to the other during the rotation 35 of said cylinders, and means to automatically and resiliently return the moving cylinder to normal position, said means being adjustably regulated by instrumentalities connected therewith, substantially as de- 40 scribed.

7. A machine of the kind set forth including a frame; a pair of stripping cylinders; a pair of rotatable shafts having bearing in the frame, said cylinders being fixed on said 45 shafts to operate on a casing passing between them; the bearings for one of said shafts comprising a pivoted bearing head and a slideable bearing head; means for drawing a sausage casing between said cylinders; means for rotating said shafts towards each other and in a direction to turn the cylinders against the run of the sausage casing; and means for positively shifting 50 and resiliently returning to normal position said slideable bearing during the rotation of said cylinders, said means being adjustably regulated by instrumentalities connected therewith, substantially as described.

8. A machine of the kind set forth including a frame; a pair of stripping cylinders rotatably arranged in opposing relation; means for moving one cylinder angularly

with respect to the other during the rotation of such cylinders, means arranged on the frame for drawing a sausage casing between 65 said cylinders; said cylinders being provided with milling cutters on the peripheral face thereof to operate on the casing drawn therebetween, and means whereby one of said cylinders may be slidably adjusted and 70 retained in normal inoperative position by a tension member, said means being adjustably regulated by instrumentalities connected therewith, substantially as described.

9. A machine of the kind set forth including a frame; a pair of stripping cylinders; a pair of shafts holding said cylinders in opposing relation, one of said shafts being fixed and the other laterally adjustable and maintained in normal position by resilient 80 means; bearings receiving said shafts and holding them to the frame; the bearings for one of said shafts being movably mounted in the frame whereby to adjust one cylinder angularly with respect to the other; said 85 cylinders being provided with milling cutters on the peripheral faces thereof to operate on a sausage casing drawn therebetween, said means adjustably regulated by instrumentalities connected therewith, substan- 90 tially as described.

10. A machine of the kind set forth including a frame, a fixed and movable stripping cylinder treadle, means to vary the positions of said movable stripping cylinder, 95 relative to said fixed stripping cylinder, and means to automatically return said movable cylinder to normal position after being moved, said means being adjustably regulated by instrumentalities connected therewith. 100

11. In mechanism of the kind described, a rectangular frame having side members, end members, and supporting standards therefor, a fixedly mounted shaft and an 105 adjustably mounted shaft transversely carried on said side members, said adjustable shaft being rotatably secured at one end in a bearing head revolvably mounted on one of said side members, the other end of said 110 adjustable shaft being swingable about a vertical axis, by means of said bearing head, a stripping cylinder secured to each of said fixed and adjustable shafts and means resili- 115 ently adjustable whereby said adjustable shaft may be resiliently put into cooperative relation with said fixed shaft through said stripping cylinders, and additional means to vary and regulate said resiliently adjustable means. 120

In testimony whereof I have signed my name to this specification.

IRVING WILLIAM ROSS.
